(57) **CLAIM**

I claim the ornamental design for an ice tray for refrigerator, as shown.

DESCRIPTION

FIG. 1 is a front/right-side/top perspective view of an ice tray for refrigerator showing our new design;
FIG. 2 is a front-side elevational view thereof;
FIG. 3 is a rear-side elevational view thereof;
FIG. 4 is a left-side elevational view thereof;
FIG. 5 is a right-side elevational view thereof;
FIG. 6 is a top-side elevational view thereof; and,
FIG. 7 is a bottom-side elevational view thereof.
